TAPE-WINDING APPARATUS

Werner Schiebeler, Eutingen, Baden, and Peter Renner, Neuenburg, Wurttemberg, Germany, assignors to International Standard Electric Corporation, New York, N.Y., a corporation of Delaware

Filed Apr. 28, 1964, Ser. No. 363,173

Claims priority, application Germany, May 24, 1963, 20,639

3 Claims. (Cl. 242—67.1)

This invention relates to tape-winding and, more particularly, to a method of winding tape in the configuration of a figure 8.

In the conventional manner, flat elongated material such as punched tape, wound in a roll in the configuration of a circle, may be unwound only from the outside. If the tape were unwound from the inside, a twist would appear once per winding, condemning the unrolling to failure.

It is common practice to wind-up short lengths of perforated tapes, film strips, etc., in a figure 8 pattern over the thumb and forefinger. Because of the absence of a mechanical windup device, this method has been restricted to primitive manual use only.

Accordingly, the principal object of this invention is to provide mechanical means for winding up a flat elongated material, such as punched tape, into a figure 8 pattern.

A further object of the invention is to provide a mechanism for winding of tape, wherein the tape will always be ready for evaluation obviating any need for rewinding.

Another object of the invention is to provide a roll of tape in which the end of the tape lies still during windoff so that it may be connected to the beginning of the next roll, for continuous evaluation of several tapes in succession.

The foregoing objects of the invention may be realized by making use of the principle that a point lying on the circumference of a rotating circle and moved orthogonal to the rotating plane of said circle will take the shape of a helix, one helix described per rotation. The present invention is based on the consideration that this helix will complete a double helix which is closed on itself and whose projection onto a plane represents figure 8 pattern, when the circle undergoes a second rotation, when moving the point toward whence it came.

Providing means to wind tape in accordance with the aforementioned principle will accomplish said objects. The above-mentioned and other features and objects of this invention will become more apparent by reference to the following description taken in conjunction with the accompanying drawings, in which:

FIGURE 1 is a side view of one embodiment of the windup unit according to the invention;

FIGURE 2 is a sectional view of the device shown in FIGURE 1 taken along the line A—A of FIGURE 1;

FIGURE 3 is a sectional view of the device shown in FIGURE 1 taken along the line B—B of FIGURE 1;

FIGURE 4 is a side view of a double winding wound-up with the device shown in FIGURE 1; and

FIGURE 5 is a perspective view of a storage container used to store double windings of the type produced by the invention in question.

Referring to FIGURE 1 of the drawings, a first embodiment of the invention is shown. Generally the invention consists of a rotating winding-up body, which is displaced laterally in accordance with a predetermined standard, upon which a tape is fed, thereby causing the tape to be rolled onto the winding-up body in a figure 8 pattern. In detail, there is arranged a winding-up body 8 in an axially displaceable manner on its shaft 11, said

2

shaft being driven by the driving means 6. A slot 17, shown in detail at the section taken on line A—A of FIGURE 2, cuts the cylinder to about three-quarters of its diameter, and extends transversely in relation to its axis; thereby the winding-up body 8 is subdivided into a right-hand guide drum 8a and the actual winding-body 8b, which is designed as a hollow cylinder. In the surface of the guide-drum 8a, designed as a cylinder, there is a groove 12 cut in the shape of a figure 8 thereabout.

10 A stationary shuttle 7 is arranged to slide in this groove causing the wound-up body, on two of its rotations, to perform an axial to-and-fro movement. According to the section taken on line B—B of FIGURE 3, the shuttle 7 is designed so that it can pass the crossing or intersecting point of the groove 12 smoothly; i.e. without an unsteady change of direction. The winding body 8b is divided by a slot 16 extending in the axial direction thereof, so that a double winding wound thereon may be easily pulled off when the cylinder is pressed together. To this end, the winding core 8b is traversed by a screw 14; by tightening of the wing nut 13 thereof, it is possible to reduce the diameter of the core. Since in the present example of embodiment the winding core is moved to-and-fro, the tape guide 15 must remain stationary. In order to guarantee a proper winding-up of the tape, the tape guide is arranged as close as possible to the circumference of the double winding, and always in the same space relation thereto. This is accomplished by having the tape guide pulled close to the double winding by the action of a spring. The distance between the tape guide and the double winding is kept constant by a roller running on the double winding, with the roller being rotatably arranged on the same arm as the tape guide.

FIGURE 4 shows a side view of a double winding 35 wound-up with the aid of this device. It is clearly recognizable that this double winding consists of the two tape rolls 1 and 2, which at point 3, are placed on top of each other in the form of crossing layers. The double winding has the shape of a folded figure 8. The inside end of the double winding must be let out between the two windings; the tape may then be pulled off from this inside end of the static double winding. Since the tape is alternately pulled off the roll 1 and the roll 2 with each time an opposite sense of winding, the twists annul each other, so that an untwisted or twist-free tape is always available for evaluation purposes.

FIGURE 5 shows a container for a double winding. This box is provided with two recesses 18 and 19 through which both the beginning and the end of the double winding are led out. After one winding has been pulled out completely, and when the tape of the next winding runs through the empty box, the loosely mounted cover or lid may be removed, and the bottom portion of the box pulled away from underneath the passing tape. The storage container for the next winding may then be inserted in its place.

While we have described above the principles of our invention in connection with specific apparatus, it is to be clearly understood that this description was made only 60 by way of example and not as a limitation to the scope of the invention as set forth in the objects thereof and in the accompanying claims.

We claim:

1. Apparatus for winding flat elongated material such as punched tape into a defined configuration comprising: 65 a winding body upon which said tape is to be rolled; a cylinder grooved with the defined configuration pattern thereupon, said cylinder and said winding body being in the form of a single cylinder subdivided by a slot extended normally in relation to its axis; a stationary shuttle communicating with the groove

of said cylinder causing said winding body to move in accordance with the grooved pattern; means to guide said tape onto said winding body; and driving means for said winding body.

2. Apparatus as in claim 1, wherein said configuration is in the form of a figure 8 and said groove is cut into a pattern of figure 8 wound about said configuration defining cylinder, causing said winding body to move to-and-fro during its rotation thereby causing the tape wound thereupon to assume a figure 8 pattern.

3. Apparatus as in claim 1, wherein said winding body portion of said cylinder is slit in its longitudinal direction and further includes a screw and wing nut arrange-

ment for reducing the diameter of the winding body for pulling off the winding wound thereupon.
